[57] CLAIM

The ornamental design for a hair or foot band, as shown and described.

DESCRIPTION

FIG. 1 is a perspective view of a hair or foot band showing my new design;

FIG. 2 is a side elevational view thereof;

FIG. 3 is a top plan view thereof; and

FIG. 4 is another perspective view thereof.

The broken line portions of FIGS. 1 and 4 are for illustrative purposes only and forms no part of the claimed design.

FIG. 1FIG. 2*FIG. 3*FIG. 4
